UNITED STATES PATENT OFFICE.

WILLIAM ROPER, OF PHILADELPHIA, PENNSYLVANIA.

METAL CASEMENT.

1,012,225.

Specification of Letters Patent. Patented Dec. 19, 1911.

Application filed February 1, 1911. Serial No. 605,936.

To all whom it may concern:

Be it known that I, WILLIAM ROPER, a citizen of the United States, residing at Philadelphia, in the county of Philadelphia and State of Pennsylvania, have invented 5 certain new and useful Improvements in Metal Casements, of which the following is a specification.

My invention relates to improvements in 10 metal casements, particularly having reference to hinged sashes, or transoms, and their supporting structures, the object of the invention being to provide improvements of this character which will, when closed, 15 exclude the outside air and form a tight closure.

A further object is to provide a transom structure of this character in which when closed, at all points, double metallic contacts 20 are formed between sections of the transom and frame.

A further object is to provide an improved construction of transom and frame at the 25 point of hinged connection to exclude the weather at this point.

With these and other objects in view, the invention consists in certain novel features of construction and combinations and arrangements of parts, as will be more fully 30 hereinafter described and pointed out in the claims.

In the accompanying drawings: Figure 1, is a view in elevation from the outside of one of the frame sections showing the transom in closed position. Fig. 2, is a view in section on the line 2—2 of Fig. 1. Fig. 3, is a view in section on the line 3—3 of Fig. 1. Fig. 4, is a view in section on the line 4—4 of Fig. 1 but showing the transom 40 in open position. Fig. 5, is a view in section on the line 5—5 of Fig. 1. Fig. 6, is an enlarged sectional view at the point of hinge connection taken on line 4—4 but showing the transom in closed position, and Figs. 7, 45 8, 9, 10, 11, and 12, are views in section on an enlarged scale on the lines 7—7, 8—8, 9—9, 10—10, 11—11, and 12—12 respectively of Fig. 1.

In constructing my improvements, I employ frame and transom bars of an improved construction which will be hereinafter pointed out.

Referring first to the frame, the outside bars 1 of which, both vertical and horizontal, 55 are shown most clearly in section in Fig. 11.

The rest of the frame is made up of horizontal and vertical series of interlocked bars 2, all of which are of the shape in cross section shown most clearly in Fig. 12.

Bars 1, and 2, as are all of the other bars 60 of the structure herein referred to, are of rolled metal and embody maximum strength, their precise shape having to do not only with ornamentation, but with strength, durability and interlocking features, the bars 1 being especially adapted 65 for locked engagement with their frames or with the walls as is well understood in this art.

The intermediate or filler bars of the transom are like bars 2 in cross section, and they 70 are vertically and horizontally disposed at right angles to each other and interlocked, and at their ends secured to the outside bars of the transom.

The upper and the side bars 3, and 4, respectively of the transom are like bars 2 in cross section, while the bottom bar 5 of the transom is more like bar 1 in cross section, and for purposes of clearness, these several 80 forms of bars will now be described.

Bars 1, on their outer faces at both edges, are provided with flanges 6, and on their inner faces, at one edge, they are made with ornamental beads 7 against which the glass 85 8 is held. Bars 2 and 4 are provided at their outer edges, with double beads constituting heads 9, and the bar 5 is precisely like bars 1, except that one of the flanges 6 is omitted. To the outer face of bar 5, a 90 metal strip 10 is secured, and when the transom is closed, engages against the outer end of bar 2 of the frame. On this bar 2, constituting the lower bar of the transom opening, an angle-iron bar 11 is secured, and 95 against which the inner edge of bar 5 engages, so that at two points shown at 12 and 13 respectively, there is engagement of metal against metal to exclude the weather. To the upper face of the bar 3, at the top of the transom, a channel-iron bar 14 is secured, with its outer flange 15 shorter than its inner flange 16. When the transom is closed, the outer flange 15 engages the head 100 9 of the top bar 2 of the transom opening, and the longer flange 16 engages the inner edge of said bar, causing a double contact of metal against metal as shown at 17 and 18 respectively to exclude the outside air. The vertical outside bars 4 of the transom. 110

throughout the upper half of their length, have secured thereto channel bars 19, the outer flanges 20 of which being shorter than the inner flanges, and bearing against the heads 9 of the vertical bars 2 of the transom opening, when the transom is in closed position, while the larger flanges 21 engage against the inner edges of said bars, forming a double metal contact at 22 and 23. To 5 the lower half of the vertical bars 2, constituting the transom opening, channel bars 24 are secured, and their inner flanges 25 are shorter than their outer flanges 26. The inner flanges, when the transom is closed, 10 bear against the heads 9 of bars 4, and the longer flanges 26 bear against the inner edges of the bars 4, so that there are two points of contact of metal against metal as 15 shown at 27 and 28 respectively. The flanges 21 and 26 of the bars 19 and 24 respectively meet end to end as shown in Fig. 6; and to these flanges the leaves 29 of 20 hinges 30 are secured, the opening movement of the transom being limited by shoulders 31 on the hinges.

To exclude the outside weather from entrance at the point of juncture of the bars 19 and 24, the outside flanges 20 and 25 respectively are extended as shown most 30 clearly in Fig. 6. The flange 25 is bent backward as shown at 32, and the extended portion 33 of the flange 20 is beveled to snugly fit against the bent portion 32, and form a snug fit when the transom is closed. 35 It will therefore be noted that throughout the entire outline of the transom, when said transom is in closed position, there is a double contact of metal against metal as above pointed out to exclude the outside air, 40 and that the air is also excluded at the hinge joint by means of the extended flanges 32 and 33, and I therefore believe I have produced a structure embodying features of decided advantage over what has heretofore 45 been done in this art.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what 55 I claim as new and desire to secure by Letters Patent is:

1. In a structure of the character described, the combination with an angle bar metal frame, an angle bar metal transom hinged in said frame, a flat bar secured to the outer edge of the lower transom bar, and an angle bar secured to the inner edge of the frame bar, said angle bars of the frame and transom being so shaped and said flat bar 60 and the angle bar secured to the frame bar

being so arranged that double metallic contacts are provided throughout the entire outline of the transom when the said transom is closed, substantially as described.

2. In a structure of the character described, the combination with an angle bar metal frame, and an angle bar metal transom hinged therein, of a channel bar secured to the angle bar at the upper end of the transom, one member of said channel bar engaging a head on the outer edge of the angle bar of the frame, and the other member of said channel bar engaging the inner edge of the frame bar, a bar secured to the lower angle bar of the transom at its outer edge, 70 and engaging the outer edge of the frame bar, and an angle bar secured to the frame bar and engaging the lower bar of the transom at its inner edge, substantially as described.

3. In a structure of the character described, the combination with an angle bar metal frame, an angle bar metal transom hinged in said frame, a bar secured to the outer edge of the lower transom bar, and a bar secured to the inner edge of the frame bar, channel bars secured to the vertical bars of the transom, above the hinged connection and engaging heads on the outer edges of the frame bars, and engaging the inner edges of the frame bars, channel bars secured to the vertical members of the frame bars below the hinged connection and engaging heads on the outer edges of the transom bars, and engaging the inner edges of the transom bars, said angle bars of the frame and transom so shaped that double metallic contacts are provided throughout the entire outline of the transom when the said transom is closed, substantially as described.

4. In a structure of the character described, the combination with a frame, and a transom hinged therein, of a channel bar secured to the upper bar of the transom and engaging a head on the outer edge of the frame bar, and the inner edge of the frame bar, a bar secured to the lower bar of the transom and engaging the outer edge of the frame bar, an angle bar secured to the frame bar and engaging the lower bar of the transom at its inner edge, channel bars secured to the vertical bars of the transom above the hinged connection and engaging heads on the outer edges of the frame bars and engaging the inner edges of the frame bars, channel-irons secured to the vertical members of the frame bars below the hinged connection and engaging heads on the outer edges of the transom bars and engaging the inner edges of the transom bars whereby said aforementioned bars compel a double metal contact at all points throughout the outline of the transom, substantially as described.

5. In a structure of the character described, the combination with a frame, and a transom hinged therein, of a channel bar secured to the upper bar of the transom and 5 engaging a head on the outer edge of the frame bar, and the inner edge of the frame bar, a bar secured to the lower bar of the transom and engaging the outer edge of the frame bar, an angle bar secured to the frame 10 bar and engaging the lower bar of the transom at its inner edge, channel bars secured to the vertical bars of the transom above the hinged connection and engaging heads on the outer edges of the frame bars and 15 engaging the inner edges of the frame bars, channel-irons secured to the vertical members of the frame bars below the hinged connection and engaging heads on the outer edges of the transom bars and engaging the inner edges of the transom bars whereby 20 said aforementioned bars compel a double metal contact at all points throughout the outline of the transom, the outer flanges of all of said channel bars extended beyond the 25 main portions of the bars, the upper end of the flanges of the lower channel bars bent inward and the outer flanges of the upper channel bars beveled to engage said inwardly bent flanges of the lower channel
- bars when the transom is closed, substantially as described. 30
6. In a structure of the character described, the combination with a metal frame, and a transom in said frame, of channel bars secured to the vertical members of the frame 35 and extending half way up the frame, channel bars secured to the vertical members of the transom and extending half way down said transom, and abutting against the ends of said first-mentioned channel bars, hinges 40 secured to the channel bars of the transom and frame, pivotally supporting the transom in the frame, the outer flanges of all of said channel bars extended at the point of juncture of said channel bars, the extended 45 flanges of the lower channel bars bent inwardly, and the lower edges of the extended flanges of the upper channel bars beveled to engage said inwardly bent flanges when the transom is closed, substantially as described. 50

In testimony whereof I have signed my name to this specification in the presence of two subscribing witnesses.

WILLIAM ROPER.
